UNITED STATES PATENT OFFICE.

ELBERT W. GAYLORD, OF CLEVELAND, OHIO.

METAL SEAL.

SPECIFICATION forming part of Letters Patent No. 371,884, dated October 18, 1887.

Application filed June 8, 1887. Serial No. 240,654. (No model.)

To all whom it may concern:

Be it known that I, ELBERT W. GAYLORD, of Cleveland, in the county of Cuyahoga and State of Ohio, have invented certain new and useful Improvements in Metal Seals; and I do hereby declare the following to be a full, clear, and exact description of the invention, such as will enable others skilled in the art to which it pertains to make and use the same.

10 My invention relates to improvements in metal seals for sealing cars and various uses, in which a locking-strip of thin metal having a hole in either end is bent double and secured by a rivet of soft material—such, for instance, 15 as lead. An eyelet of harder material is mounted on the shank of the rivet in position to pass through the holes of the locking-strip and to be expanded by the upsetting of the rivet, to the end that such seal cannot be 20 broken and the parts reassembled without leaving indications of the seal having been tampered with.

In the accompanying drawings, Figures 1 and 2 are elevations in section, the one showing 25 the eyelet detached and the other showing the eyelet in position on the rivet. Fig. 3 is a plan of the locking-strip with the rivet in position at one end of the strip. Figs. 4 and 5 are elevations in section showing the parts 30 assembled and showing the rivet and eyelet before and after upsetting.

A represents the locking-strip, the same being usually made of tin or other thin plate metal, with rivet-holes at either end thereof. 35 The locking-strip is inserted in the hasp and staple and bent back double, and the ends secured by rivets. Lead rivets have more commonly been employed for this purpose, such rivet having a large flat head on which 40 to stamp the number of station sending and perhaps the initial letters of the name of the shipping line or road, or whatever may be desired to stamp thereon, such letters or characters being pressed on simultaneously with 45 the upsetting of the rivets.

There was this defect in the lead rivets, to wit: With adroit manipulation, with the aid of suitable tools, the upset ends of the rivet could be compressed, so that the rivet could 50 be removed and again placed in position and upset, leaving little or no indication that the seal had been tampered with. Eyelets have

been employed for this purpose in place of the rivets, and, although these eyelets could not well be removed and reriveted, the eyelet could 55 not well be stamped, as desired, and without such stamping the seal was of little value, as in case the eyelets were removed other eyelets could be used to replace the broken ones.

In carrying out my invention I employ a 60 lead rivet, B, or, if not of lead, of other suitable soft material that may be easily stamped and upset, such rivet having a broad flat head suitable for stamping thereon the desired letters, figures, or characters. Upon the shank 65 of the rivet is placed an eyelet, C, the latter being firmly pressed on, so as to keep its place in shipping and handling the goods. The rivet has a conical depression, b, in the end of its shank that serves to center the upsetting- 70 tool.

In Fig. 4 the combined rivet and eyelet is shown in position in the two ends of the locking-strip. By means of a hand-tool substantially the same as heretofore employed for this 75 purpose the rivet-head is stamped, and at the same operation the shank of the rivet is upset approximately in the form shown in Fig. 5, the eyelet being expanded by upsetting the leaden shank and the outer end of the eyelet 80 being crimped inward and made partially to cover the end of the rivet, thus preventing the leaden shank from being compressed or reduced in size.

It is evident that the eyelet, after having 85 been swelled out in the center and crimped over in the manner shown, could not be successfully removed and replaced.

What I claim is—

As a new article of manufacture, a metal 90 seal consisting of a soft-metal rivet having a head and shank and a cylindrical eyelet, the latter being as long or approximately as long as the shank and adapted to fit and be expanded or upset with said shank, substantially 95 as set forth.

In testimony whereof I sign this specification, in the presence of two witnesses, this 31st day of May, 1887.

ELBERT W. GAYLORD.

Witnesses:

CHAS. H. DORER,
ALBERT E. LYNCH.
